COMBINED SUPPORT AND BOLT FOR A TOILET SEAT HINGE SET

Leslie H. Coggins, Meriden, Conn., assignor to The J. B. Coggins Manufacturing Company, Meriden, Conn., a corporation of Connecticut

Filed July 20, 1961, Ser. No. 65,993

Term of patent 14 years

(Cl. D4—5)

FIGURE 1 is a top plan view of a combined support and bolt for a toilet seat hinge set embodying my new design;

FIGURE 2 is a front elevational view thereof;

FIGURE 3 is a rear elevational view thereof, a portion of the bolt being broken away for convenience of illustration, and

FIGURE 4 is a side elevational view thereof, the opposite side being substantially the same in appearance.

I claim:

The ornamental design for a combined support and bolt for a toilet seat hinge set, as shown and described.
